UNITED STATES PATENT OFFICE.

NICK LETZLER, OF NAPOLEON, INDIANA.

FIRE-ESCAPE.

SPECIFICATION forming part of Letters Patent No. 536,088, dated March 19, 1895.

Application filed January 14, 1895. Serial No. 534,892. (No model.)

To all whom it may concern:

Be it known that I, NICK LETZLER, a citizen of the United States, residing at Napoleon, in the county of Ripley and State of Indiana, 5 have invented a new and useful Improvement in Fire-Escapes, which improvement is fully set forth in the following specification and accompanying drawings, in which—

Figure I is a side view of my improved fire escape, partly in section; Fig. II, a front view; Fig. III, a detail view showing the device enclosed in a flexible chute, and Fig. IV, a view of the device in operation.

The object of my invention is to provide a 15 simple and reliable apparatus designed to afford a safe and ready means of escape for inmates of burning buildings.

The invention consists in the novel construction and combination of parts hereinafter fully described and claimed.

In the said drawings the reference letter A indicates a pulley block containing sheaves 2 3 4 and 5, the upper one of which is journaled in bearing blocks 6 which move in vertical 25 slots 7. Each slot contains a compressible spring 8, the purpose of which will be herein-after explained. An endless rope 9 passes around the upper sheave 2, thence downwardly between and bearing upon the inner 30 sides of the intermediate sheaves 3 and 4. Below these it separates and bears upon the outer sides of the lower sheave 5. The lower end of the coil encircles a sheave 10 in a block 11 from which a rope extends to a grappling 35 block 12 provided with a hook 13. The object of the grapple and its adjuncts is to provide means for attaching the tackle to a fixed object outside of the building in order that when desired a tension may be exerted upon 40 the endless rope.

The block A is connected by a pin or bolt 15 to a plate 16 having eyes to receive bails 17 the upper extremities of which are provided with hooks which engage the upper 45 cross bar 19 of a frame 20. This connection is designed to form a practically universal joint so that if by reason of any obstruction or a fire beneath the window the device cannot be suspended perpendicularly from a

window the lower end may be easily moved 50 to either side or carried out into the street. The said cross bar 19 is extensible so that it may be adapted to windows of various widths, and has right angled pointed ends to engage the window casing. The lower cross bar of 55 the frame is provided with hooks 21 and 22 by which it is secured to the window sill when in use.

The operation of the device is as follows: The frame being set and the rope and tackle 60 being cast out of the window, as shown in Fig. III, the operator seizes one of the ropes. His weight causes the upper sheave 2 to bear upon the spring and the rope is thus compressed between the upper and the intermediate 65 sheaves. It follows that the friction produced in this manner is in proportion to the weight of the operator and the speed of his descent will be governed accordingly. It is therefore obvious that any additional weight will increase the friction and the rate of movement 70 will not be materially affected. It is evident that if the grappling hook 13 be attached to a fixed object outside of the building, as hereinbefore described, an assistant, by means of 75 the tackle, may regulate the tension and consequent friction in such a manner as to govern the movement independent of any effort on the part of the operator.

The object of the flexible chute is to remove the timidity of persons who, in the absence of surroundings which offer even an apparent protection, would refuse to take the first step required to insure their own safety.

What I claim as new is—

In a fire escape, the combination with a frame provided with an extensible transverse bar adapted to engage the inner sides of a window or door casing, with the herein described pulley block containing a sheave journaled in vertically movable bearings normally upheld by springs, the supplemental friction sheaves adapted to co-operate with the said movable sheave, the separating sheave beneath the supplemental sheaves, the endless rope passing over the movable sheave and between the supplemental sheaves, the pulley block and sheave adapted to engage

the lower loop of the endless rope, the tension tackle connecting the said pulley block with a grappling block, and the flexible chute adapted to envelop the endless rope and its
5 adjuncts, all constructed and arranged substantially as and for the purpose herein specified.

In testimony that I claim the foregoing I have hereunto set my hand, this 1st day of January, 1895, in the presence of witnesses.

NICK LETZLER.
